UNITED STATES PATENT OFFICE

JOHN P. COLEMAN, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY INTERLOCKING APPARATUS

Application filed September 21, 1929. Serial No. 394,823.

My invention relates to interlocking apparatus for the control of railway switches and signals. One feature of my invention is the provision, in apparatus of this character, of means for safely permitting the complete and uninterrupted movement of a switch lever from one extreme position to the other to effect switch operation, thereby expediting the manipulation of traffic.

10 I will describe certain forms of apparatus embodying my invention, and will then point out the novel features thereof in claims.

In the accompanying drawings, Fig. 1 is a vertical sectional view showing a portion of one form of interlocking machine embodying my invention. Fig. 2 is a sectional view on the line II—II of Fig. 1, looking in the direction indicated by the arrow. Fig. 3 is a horizontal view, partly in section, of a portion of the apparatus shown in Fig. 1. Fig. 4 is a sectional view on the line IV—IV of Fig. 3. Fig. 5 is a diagrammatic view showing one arrangement of apparatus and circuits utilizing the interlocking machine lever shown in Fig. 1 and embodying my invention. Fig. 6 is a diagrammatic view showing a modification of the indication controlling circuits shown in Fig. 5. Fig. 7 is a diagrammatic view showing a modification of the railway switch controlling circuits shown in Fig. 5. Fig. 8 is a view showing a switch and signal layout to which the circuits illustrated in Figs. 5, 6 and 7 may be applied.

20 Similar reference characters refer to similar parts in each of the several views.

It has heretofore been almost a universal custom in power interlocking practice to utilize a preliminary movement of a switch lever for causing operation of the corresponding switch, and a final movement of this lever to release other levers for permitting signals governing traffic over the switch to be cleared, the final movement of the switch lever being physically prevented until the switch has fully responded and has become locked in response to the preliminary movement of the lever. The medium through which this final movement of the switch lever is made possible, is termed the

“indication system”, and while varying in detail in various forms of interlocking systems, it is in principle and purpose the same in all of them. Mere release of the switch lever by an electric impulse from the switch to permit the final movement of the lever, as was customary in early indication systems, involved an active state of the system during only the operation of the switch in response to operation of its lever, and, consequently, it afforded no means for nullifying subsequent effects of a false indication, that is, a false release of the lever in the event of failure of the switch to fully respond to the preliminary lever movement. To avoid such ill effects, the indication system was modified to include as an adjunct to the release of the lever, means for controlling the signal operating circuits peculiar to traffic over the switch by the lever releasing means. In this way, a switch failing to coincide with its lever at any time effectively prevented the granting of any signal rights to traffic over the switch. Likewise, displacement of the switch after proper operation in response to its lever and after the clearing of a signal governing traffic over the switch, at once withdrew the proceed signal. Thus the switch became a continuous medium of signal control without disturbing the original control of the lever in response to switch operation.

This continuous control of a signal by its associated switch raises a question as to the necessity for the two distinct movements, that is, the preliminary and the final movement of the switch lever. It seems reasonable to assume that the continuous control of the signal by the switch, if effective to safeguard traffic in the event of failure of the first provision, should, if constructed with especial regard for such service, be dependable enough to serve alone as the indication medium, and my present invention is based upon this assumption.

Referring now to Fig. 1, the reference character 1 designates the frame of a power interlocking machine, in the upper portion of which is mounted a manually operable switch lever L constructed in accordance

with usual and well known practice. This lever is journalled to oscillate through an angle of 60° around its longitudinal axis, oscillations being caused by a manually operable handle which is attached to the right-hand end of the lever but is not shown in the drawings. This lever co-acts with other levers in the machine through the medium of the usual mechanical interlocking which is indicated at 3 in the drawings, and the lever is also provided with the usual electric lock 2 which, however, forms no part of my present invention.

A vertical shaft A is mounted in bearings 4 and 35 in the frame 1, and is operatively connected with the lever L through the medium of mitre gears 11 and 12, whereby the shaft A is oscillated through an angle of 60° in response to a full movement of the lever L. This shaft A carries a roller 10^A on which are mounted metal bands (not shown) which establish and interrupt contact with flat contact springs suitably supported in an insulated plate carried by the machine frame 1. These metal bands and contact springs are omitted from Fig. 1 to simplify the drawing; the contacts which are associated with this roller are designated 24^A, 23^A, etc., in the diagrammatic views of the accompanying drawings.

In accordance with the present invention, no restriction is imposed on the full operation of the lever L when a change in switch position is to be made. The lever is thrown fully from normal position to reverse position or vice versa to effect switch operation, and the lever governing the signals which control traffic over the switch being thus mechanically released, may be operated before the switch has fully responded or even without its response at all. Such a condition, however, will not result in a proceed signal being given when the switch does not properly respond to its lever movement, because of the following further apparatus associated with the switch lever.

An auxiliary shaft B is mounted in bearings 5 and 6 in the machine frame 1, and is loosely coupled with the shaft A in such manner as to permit a partial movement of the lever L without mechanical interruption, but to prevent a complete movement of the lever unless the shaft B responds through the medium of apparatus which I will describe hereinafter. This lost motion coupling comprises a collar 7 attached to the lower end of shaft A and provided with a radially extending lug 7^a from which a stud 8 projects downwardly. This stud lies between two arms 9^a and 9^b projecting radially from a collar 9, which is attached to the upper end of the shaft B. When the lever L is in its normal position, the parts of this coupling occupy the relative positions in which they are shown in Fig. 2, from which

it will be seen that the lever L and shaft A may be rotated counter-clockwise through an angle of about 30° before the stud 8 engages the arm 9^b, whereupon if the shaft B then rotates in counter-clockwise direction through an angle of about 30° the final motion of the shaft A through its second stage of 30° may be completed without mechanical interference by the shaft B. If the shaft B then responds to switch operation as hereinafter explained, by making its final motion of 30° in counter-clockwise direction, the parts will occupy the same relative positions as in Fig. 2, except that they will all be swung in counter-clockwise direction through an angle of 60° .

The shaft B carries rollers 10^B, and associated with these rollers are electrical contacts similar to those associated with roller 10^A. These contacts are designated by the reference character 25^B in Fig. 5.

The shaft B is operated by a motor device which is illustrated at the lower end of Fig. 1, and also in Figs. 3 and 4. Attached to the lower end of shaft B is a crank 13, and pivotally connected with this crank on opposite sides of the shaft B are two links 15, 15, which are in turn pivotally connected with pistons 16 operating in two cylinders 14^R and 14^F. These cylinders and the devices associated with them are alike, and, consequently, only one of them is illustrated in section in Fig. 3. Referring to cylinder 14^R, the piston 16 is of the "trunk" variety, in that it is provided with a sleeve 36 which slides with the piston in the cylinder. Screwed into the right-hand end of the cylinder is a disk 17, and sliding in this disk is a sleeve 18 on the outer end of which is a strap 18^a which limits the inward movement of the sleeve. The inner end of the sleeve 18 is provided with a flange 18^b, and between this flange and the disk 17 is a coil spring 19 which biases the piston 16 to an intermediate position in which it is shown in Fig. 3. When air pressure is admitted to the cylinder 14^R on the left-hand side of piston 16, this piston is moved outwardly, thereby compressing the spring 19 until the sleeve 36 engages the disk 17. On the contrary, the piston 16 may be moved to the left, from the position in which it is shown in the drawing, by the corresponding link 15, the piston in this case moving away from the sleeve 18, thereby leaving the inner sleeve 18 and the spring 19 in the positions in which they are illustrated.

The supply of air pressure to the cylinders 14^R and 14^F is controlled by two valves V^R and V^F, which valves in turn are controlled by magnets M^R and M^F. Referring to Fig. 4 as well as Fig. 3, when magnet M^R is de-energized, cylinder 14^R is connected with atmosphere through port 22 and exhaust 120

port 21. When this magnet is energized, however, port 22 is disconnected from the exhaust port 21 and is connected with a port 20, which is constantly supplied with air 5 under pressure, so that this air is admitted to cylinder 14^N to move the associated piston outwardly.

When both magnets M^N and M^R are de-energized, both pistons 16 occupy their intermediate positions, so that the shaft B is then biased to its intermediate position by the springs 19. When magnet M^N becomes energized, the piston in cylinder 14^N is moved outwardly, thereby swinging the 15 shaft B to its normal position, whereas when the magnet M^R is energized, piston 16 in cylinder 14^R is moved outwardly, thereby swinging the shaft B to its reverse position.

Referring now to Fig. 8, the reference 20 character F designates a railway switch which is operated by a switch mechanism E of the electropneumatic type, comprising a normal magnet N, a reverse magnet R, and a lock magnet L. Traffic in one direction 25 over this switch is governed by a signal G.

Referring to Fig. 5, the elements at the right-hand end of this view are associated with the interlocking machine, whereas the elements at the left-hand end of the view 30 are associated with the switch mechanism E of Fig. 8. The dash line A represents the shaft A of the interlocking machine lever L, and the contacts 24^A, 40^A, and 23^A are operated by the roller on this shaft. 35 The dash line B represents the shaft B of Fig. 1, and the contacts 25^B are operated by the roller on this shaft.

With the circuits in the conditions in which they are shown in Fig. 5, the shafts 40 A and B are both in their full normal positions, shaft B being held in this position because indication magnet M^N is energized by virtue of a circuit which passes from the lower terminal of battery H, through 45 line wire 38, contact 26 operated by switch mechanism E, wire 43, magnet M^N, contact 24^A, rectifier C², wire 44, contact 27, and line wire 39 to the upper terminal of battery H. The switch F is held in its normal 50 position, because the normal magnet N is energized, the circuit being from the lower terminal of battery H, through the lower arm of pole-changer 23^A, line wire 41, rectifier C³, magnet N, wire 42, and the upper 55 arm of pole-changer 23^A to the upper terminal of battery H.

Each rectifier C shown in this view is an asymmetric unit, that is, a unit which permits current to flow freely in the direction indicated by the arrow, but prevents the flow of any substantial amount of current in the opposite direction.

I will now assume that the operator desires to move switch F to its reverse position. To do this, he will swing lever L to its

reverse position. During the first portion of this movement of lever L, contact 24^A will be opened, thereby opening the circuit just traced for indication magnet M^N, with the result that shaft B will immediately move 70 to its middle position. This will permit the full and uninterrupted motion of lever L to its reverse position, and when it reaches this position, pole-changer 23^A will be reversed. Current will then flow from the lower 75 terminal of battery H, through the lower arm of pole-changer 23^A, wire 42, reverse magnet R, rectifier C⁴, wire 41 and the upper arm of pole-changer 23^A to battery H. Current will also flow from the lower 80 terminal of battery H through the lower arm of pole-changer 23^A, wire 42, lock magnet L, contact 28, rectifier C⁵, wire 41, and the upper arm of pole-changer 23^A to battery H. Magnets R and L being energized, 85

the switch mechanism E will be operated to move the switch to its reverse position. When the mechanism reaches its full reverse position, contact 28 will reverse, thereby opening the above-traced circuit for lock 90 magnet L and connecting this lock magnet with a rectifier C⁶ which is interposed in the circuit in such direction as to prevent energization of the lock magnet by current of reverse polarity from battery H. Also, 95 upon completion of the operation of the switch mechanism E, contacts 26 and 27 will be reversed, whereupon indication magnet M^R will become energized by virtue of the following circuit; from the lower terminal 100 of battery H, through wire 38, contact 26, wire 44, magnet M^R, contact 40^A (which will then be reversed), rectifier C¹, wire 43, contact 27 and wire 39 to the upper terminal of battery H. Magnet M^R being energized, 105 the shaft B will be swung to its full reverse position.

The reference character L¹ in Fig. 5, represents diagrammatically a signal controlling lever in the interlocking machine frame 110 1 of Fig. 1. Normally, this lever occupies its middle position, but when released by the mechanical interlocking bed 3, it may be moved in either direction from its middle position to close the circuits for signals governing traffic over the switch F. Interposed in the circuits for these signals are contacts 25^B operated by the shaft B of Fig. 1. Certain of these contacts are closed when the shaft is in its normal position, and other contacts are closed when the shaft is in its reverse position, but all contacts are open when the shaft is in its intermediate position. It follows that when the shaft moves to its intermediate position in response to the first portion of the movement of lever L, the circuits for all signals governing traffic over the switch F will be opened at contacts 25^B, and none of these circuits can be closed until shaft B completes its movement 115 120 125 130

to normal or reverse position in response to switch operation. It will furthermore be seen that unless the shaft B moves to its middle position in response to the preliminary portion of the movement of lever L, the movement of lever L cannot be completed, because the stud 8 will engage with one of the arms 9^a or 9^b on the shaft B and will thereby mechanically prevent a sufficient movement of the lever to cause operation of the switch.

Referring now to Fig. 6, I have here shown a modified arrangement of the circuits for controlling the indication magnets M^R and M^N. When the lever and the switch are both in normal positions, magnet M^N is energized by a circuit which passes from battery H, through contact 26, wire 43, magnet M^N, contact 45^A, normal contact 30 of a polarized relay D, winding 29 of this relay, wire 44, and contact 27 to battery H. When the lever L is reversed, contacts 32^A and 45^A, associated with the shaft A of this lever, will be reversed, thereby opening the circuit just traced for magnet M^N, with the result that shaft B will move to its middle position. After the movement of the switch mechanism is completed, contacts 26 and 27 will reverse, whereupon relay D will become energized by current of reverse polarity, the circuit being from battery H, through contact 26, wire 44, winding 29 of relay D, contact 30 of this relay, contact 45^A, wire 43 and contact 27 to battery H. This current of reverse polarity will cause polar contact 30 to reverse, whereupon magnet M^R will become energized, the circuit being from battery H, through contact 26, wire 44, winding 29 and contact 30 of relay D, contact 32^A, magnet M^R, wire 43 and contact 27 to battery H. When lever L is returned to its normal position, contacts 32^A and 45^A will be restored to their normal positions, and as soon as contacts 26 and 27 return to their normal positions relay D will again become energized in the normal direction, thereby restoring contact 30 to its normal position, with the result that magnet M^N will again become energized.

Referring now to Fig. 7, I have in this view shown means for replacing the rectifiers C of Fig. 5 by a polarized relay D¹ which is similar to relay D shown in Fig. 6. When the switch lever L is in its normal position, so that pole-changer 23^A is in its normal position, current flows from battery H, through the lower arm of pole-changer 23^A, wire 41, winding 29 of relay D¹, normal magnet N, contact 30 of relay D¹, wire 42, and the upper arm of pole-changer 23^A to battery H. Reverse magnet R and lock magnet L are both deenergized under this condition. When lever L is reversed, pole-changer 23^A will become reversed, whereupon current of reverse polarity will be supplied

to winding 29 of relay D¹, through the circuit which I have just traced, with the result that polar armature 30 of this relay will swing to its reverse position. Reverse magnet R will then be energized, the circuit being from battery H, through the upper arm of pole-changer 23^A, wire 41, relay winding 29, reverse magnet R, relay contact 30, wire 42 and the lower arm of pole-changer 23^A to battery H. Lock magnet L will be energized at the same time, the circuit being from battery H, through the upper arm of pole-changer 23^A, wire 41, magnet L, switch mechanism contact 33, relay contact 30, wire 42, and the lower arm of pole-changer 23^A to battery H. When the switch mechanism reaches its full reverse position, contacts 33 and 34 will reverse, thereby opening the circuit just traced for magnet L. When the lever L is restored to its normal position, pole-changer 23^A will return to its normal position, thereby supplying current of normal polarity to the winding of relay D¹, through the reverse magnet R. Contact 30 of relay D¹ will then return to its normal position, whereupon normal magnet N will again be energized and lock magnet L will also be energized through contact 34 of the switch mechanism. When the switch mechanism returns to its full normal position contacts 33 and 34 will be restored to the positions in which they are shown in the drawing, so that lock magnet L will again become de-energized.

Although I have herein shown and described only a few forms of apparatus embodying my invention, it is understood that various changes and modifications may be made therein within the scope of the appended claims without departing from the spirit and scope of my invention.

Having thus described my invention, what I claim is:

1. In combination, a manually operable interlocking machine lever, a railway traffic governing device responsive to complete operations of said lever, a circuit controller comprising a roller associated with said lever, means responsive to a partial operation of said lever for shifting said roller to an intermediate position, means for preventing complete operation of said lever unless said roller responds to the partial operation, means responsive to a movement of said traffic governing device for completing the movement of said roller, and means for controlling another traffic governing device by said circuit controller.

2. In combination, a manually operable interlocking machine lever, a railway traffic governing device responsive to complete operations of said lever, a circuit controller comprising a roller associated with said lever, a motor device for moving said roller, means responsive to a partial operation of

5 said lever for controlling said motor device to shift said roller to an intermediate position, means for preventing complete operation of said lever unless said roller shifts to its intermediate position in response to the partial movement of the lever, means responsive to a movement of said traffic governing device for controlling said motor device to shift said roller to its final position, and means for controlling another traffic governing device by said circuit controller.

10 3. In combination, a manually operable interlocking machine lever, a railway switch responsive only to complete operations of said lever, a circuit controller associated with said lever, means responsive to a partial operation of said lever for shifting said circuit controller to an intermediate position, means for preventing complete operation 15 of said lever unless said circuit controller responds to the partial operation, means responsive to a movement of said switch for completing the movement of said circuit controller, and means for preventing the clearing of a signal governing traffic over said switch while said circuit controller is in its intermediate position.

20 4. In combination, a manually operable interlocking machine lever, a railway traffic governing device controlled by said lever, a circuit controller comprising a roller associated with said lever, a motor device for moving said roller, means for controlling said motor device jointly by said lever and by said traffic governing device, a second traffic governing device controlled in part by said circuit controller, and means for controlling said lever by said roller.

25 5. In combination, an interlocking machine lever manually movable to normal and reverse positions, a railway switch, means for causing operations of said switch to normal and reverse positions in response to movements of said lever to full normal and reverse positions, a roller associated with said lever and having normal and reverse positions corresponding to the normal and reverse positions of the lever, a motor device comprising a normal and a reverse magnet for moving said roller to normal or reverse position according as the normal or the reverse magnet is energized and for holding the roller in an intermediate position when both magnets are deenergized, means responsive to a preliminary movement of said lever from either normal or reverse position for deenergizing both of said magnets, means responsive to operation of said switch for energizing the corresponding one of said magnets thereby completing the corresponding movement of said roller, means for preventing the clearing of a signal governing traffic over said switch unless said roller has completed its movement in response to operation of the switch, and a

30 lost motion coupling between said lever and said roller for permitting the aforesaid preliminary movement of said lever but preventing a complete movement of the lever unless the roller moves to its intermediate position in response to preliminary movement of the lever.

35 6. In combination, an interlocking machine lever manually movable to normal and reverse positions, a railway switch, means for causing operations of said switch to normal and reverse positions in response to movements of said lever to full normal and reverse positions, a roller associated with said lever and having normal and reverse 40 positions corresponding to the normal and reverse positions of the lever, means for biasing said roller to an intermediate position, a normal and a reverse indication magnet, a fluid pressure motor for moving said roller to its normal position when said normal magnet is energized, a second fluid pressure motor for moving said roller to its reverse position when said reverse magnet is energized, means responsive to a preliminary 45 movement of said lever from either normal or reverse position for deenergizing both of said magnets, means responsive to operation of said switch for energizing the corresponding one of said magnets thereby completing 50 the corresponding movement of said roller, means for preventing the clearing of a signal governing traffic over said switch unless said roller has completed its movement in response to operation of the switch, and a lost motion coupling between said lever and said roller for permitting the aforesaid preliminary movement of said lever but preventing a complete movement of the lever unless the roller moves to its intermediate 55 position in response to preliminary movement of the lever.

60 7. In combination, a railway switch, a manually operable lever for controlling said switch, a normal and a reverse indication magnet for the control of said lever, an indication circuit including said normal magnet and a rectifier connected to allow current of normal polarity to pass through the magnet, a branch for said circuit around said normal magnet and including said reverse magnet as well as a rectifier connected to allow current of reverse polarity to pass through the reverse magnet, and means controlled by said switch for supplying current 65 of normal or reverse polarity to said indication circuit according as the switch is in normal or reverse position.

65 8. In combination, a railway switch operating mechanism having a normal magnet and a reverse magnet, a polarized relay, a circuit for the winding of said relay, means controlled by the contacts of said relay for connecting said normal or said reverse magnet in said circuit in series with the relay 70

winding according as the circuit is supplied with current of normal or reverse polarity, and means including a manually operable switch controlling lever for supplying current of normal or reverse polarity to said circuit.

9. In combination, a railway switch operating mechanism having a normal magnet and a reverse magnet as well as a lock magnet, a polarized relay, a circuit for the winding of said relay, means controlled by the contacts of said relay for connecting said normal or said reverse magnet in said circuit in series with the relay winding according as the circuit is supplied with current of normal or reverse polarity, means controlled jointly by said switch mechanism and by said polarized relay for connecting said lock magnet in said circuit in multiple with the relay winding and the normal or reverse magnet whenever the mechanism and the relay do not harmonize in positions, and means including a manually operable switch controlling lever for supplying current of normal or reverse polarity to said circuit.

10. In combination, a railway switch mechanism, a manually operable lever for controlling said mechanism, a normal and a reverse indication magnet for the control of said lever, a polarized relay, a circuit for the winding of said relay having a plurality of branches, one branch including a normal contact of the relay and a reverse contact on said lever, another branch including a reverse contact of the relay and a normal contact on the lever, a third branch for said circuit including said normal magnet and a normal lever contact as well as a normal contact of said relay, a fourth branch for said circuit including said reverse magnet and a reverse lever contact as well as a reverse contact of said relay, and means controlled by said switch mechanism for supplying current of normal or reverse polarity to said circuit according as the switch is in normal or reverse position.

In testimony whereof I affix my signature.
JOHN P. COLEMAN.
